UNITED STATES PATENT OFFICE.

THOMAS WILLIAM BACHE, OF WEST BROMWICH, ENGLAND.

SHOW CASE.

Application filed October 2, 1926, Serial No. 139,193, and in Great Britain December 15, 1925.

This invention relates to improvements in show cases particularly for use with weighing machines of the platform or pedestal type wherein the load to be weighed is placed upon a platform mounted upon a base member having a vertically-disposed pillar or support which carries at its upper end the weight indicating mechanism, the latter being connected to the said platform by means of a rod or member passing up through the pillar or support.

The object of the invention is to provide an improved construction of show-case which is particularly suitable for use in combination with a weighing-machine of the above type.

Referring to the accompanying drawings:—

Figure 1 is a perspective view of a combined weighing-machine and show-case constructed in accordance with this invention.

Figure 2 is a horizontal transverse section through the show-case of the machine upon the line 2—2, Figure 1, the door being shown 25 ajar.

Figure 3 is a vertical section through the show-case upon the line 3—3, Figure 2.

Figure 4 is a front elevation to an enlarged scale of one of the show-case door 30 catches, part of the show-case framing being broken away.

Figure 5 is a section upon the line 5—5, Figure 4.

Figure 6 is a horizontal section also to an 35 enlarged scale through one of the show-case door hinges.

In carrying out the invention, the vertically-disposed pillar or support comprises a vertical elongated compartment 1 forming 40 a show-case of a rectangular cross-section through the centre of which passes the rod 2 connecting the machine platform 3 with the weight-indicating mechanism.

The frame of the show-case has a pair of 45 vertical angle-section corner members 4 and also a pair of vertical double angle-section corner members 5 all carried by the base upon which the platform 3 is mounted, the members 5 form a recess 6 in which the door 50 7 is housed when shut and also grooves 8 adapted to receive the front vertical edges of the adjacent sides 9 of the case. The door of the case preferably consists of a glass or other transparent panel mounted in 55 an angle-sectioned frame 10, the depth of the recess 6 and the thickness of the door 7

being equal, so that the front face of the door lies flush with the front faces 11 of the members 5. The sides 9 of the case are preferably of glass or other transparent material, 60 while the back of the case is constituted by a mirror 12 backed by a metal or other suitable back-plate 13. The door is provided with catches 14 carried by the angle-sectioned frame 10 thereof and adapted to engage notches or apertures 15 in the wall 16 of the right-hand corner member 5. The door hinges 17 are let into the corresponding wall 16 of the left-hand corner member 5 one hinge-member being screwed to blocks 70 18 disposed in the groove 8 of the said corner-member, the glass panel 9 being notched or recessed to accommodate the same. The other hinge-member is screwed to the door frame-member 10 as shown at Figure 6. Instead of a single door being employed a pair of doors may be used hinged at their outer edges and locked together at their inner adjacent edges when closed, while instead of the door or doors forming the front side of 80 the case, as illustrated, they may be disposed at either side or at the back in which case the corner members of the case frame would be arranged accordingly. One or more pairs of rods or brackets 19 held in position by screws 20 are provided for supporting one or more shelves 21 within the case. The shelves are preferably made of glass and are split into two halves upon their longitudinal centre, i. e. from side to side of 90 the case to facilitate their removal from around the rod 2 which is accommodated in opposed recesses or notches 22 disposed centrally in the meeting edges of the two halves of the shelf.

As shown in the drawings, the bottom of the show-case is considerably elevated above the platform 3, and below the said show-case metal panels are secured to the front and sides of the pillar frame. The glass panels 95 of the show-case are thus protected from damage when a person stands upon the platform or when goods are placed thereon.

Having fully described my invention, what I desire to claim and secure by Letters Patent is:—

A show-case comprising a base, a vertical frame consisting of four corner uprights carried by the base the two front uprights each being of an integral double angle-section forming a rearwardly-open channel and a set-back flange at right-angles to the inner

flange of the channel and integral therewith, a pair of glass walls respectively engaged in the channels of the two said uprights to form opposite sides of the show-case, a wall 5 secured to the rear uprights to form the back of the show-case, a hinged door forming the front of the show-case and engaging, when closed, the set-back flanges of the channelled uprights so as to lie flush with the outer 10 faces of said uprights, hinges on one edge of the door, the inner side flange of the channel of one of the front uprights having gaps

to receive them, members located within the said channel opposite to the hinges, the edges of the glass side walls of the case having 15 gaps to receive the said member, means for securing the hinges directly to the said members, shelf-supporting brackets carried by the frame uprights within the show-case, and shelves supported upon the said brackets for displaying goods thereon.

In testimony whereof I have hereunto set my hand.

THOMAS WILLIAM BACHE.
